APPARATUS FOR AND METHOD OF MAKING BOILER HEADERS

Application filed April 6, 1928. Serial No. 268,043.

This invention relates to improvements in apparatus for and method of making boiler headers.

The principal object of the invention is the provision of such an apparatus whereby boiler headers may be made by means of die and mandrel, and in which the metal of the header will be uniformly bent and pressed from one end to the other, with the elimination of weak or uneven spots or places and without breakage or cracking or tearing.

A further object of this invention is the provision of such an apparatus in which the dies by which the header is shaped are pressed gradually and progressively from one end to the other of the metal, in contradistinction to complete and instantaneous pressure over the entire extent of the metal at one time.

A further object of this invention resides in the method of making a boiler header by which the same is shaped from a blank or tube of metal by die pressure beginning at one end and applied progressively throughout the length of the metal to the other end.

A further object of this invention resides in the making of a boiler header having undulatory sides staggered with reference to each other and having inclined seats provided on the top thereof by shaping a blank or tube by die pressure of side dies and a top die, the pressure beginning at one end and then applied progressively throughout the length of the blank to the other end.

A further object of this invention is the provision of an apparatus of the character described in which side dies are mounted so as to be actuated and have a scissors-like action in engaging the sides of a blank to be formed into the completed header, whereby the blank will be engaged and pressed initially at one end and progressively from that end throughout its length.

A further object of this invention is the provision of a knockdown form of mandrel which may be readily placed in position within the blank and removed therefrom when the shaping operation is completed.

To the accomplishment of the foregoing and such other objects as may hereinafter

appear, this invention consists in the construction, combination and arrangement of parts and the method hereinafter described and then sought to be defined in the appended claims, reference being had to the accompanying drawings, forming a part hereof and which show for the purpose of illustrative disclosure one embodiment of my invention in an apparatus adapted to practice the process, it being expressly understood, however, that various changes may be made in practice within the scope of the claims without digressing from my inventive idea.

In the drawings—

Figure 1 represents an end elevation, parts being shown in section, of one form of apparatus constructed to embody my invention and to be operated according to my method.

Figure 2 is a vertical longitudinal section taken substantially on line 2—2 of Figure 1.

Figure 3 is a top plan view of the apparatus shown in Figure 2, parts being broken away to facilitate the disclosure.

Figure 4 is a side elevation of the view shown in Figure 3.

Figure 5 is a detailed perspective of one of the side die members.

Figure 6 is a bottom plan view of the top die member.

Figure 7 is a section taken substantially on line 7—7 of Figure 2, showing the top die member and the method of securing and operating the same.

Figure 8 is a top plan view of a completed header, parts being broken away to show the mandrel in position.

Figure 9 is a cross section taken substantially on line 9—9 of Figure 8.

Figure 10 is a section of half of a header and the enclosed mandrel taken on line 10—10 of Figure 8.

Figure 11 is a perspective view of a completed header of one form.

Heretofore headers for boilers have been made by means of die-shaping operations in which the entire die or dies are brought into contact with the blank or tube and the entire length of the blank or tube shaped at

one time. Because of this operation the metal of the blank or tube must give in certain places more than in others, which results in the formation of headers of uneven thickness of material, and also results in breakage of a large number of blanks and cracking of the headers.

The purpose of my apparatus and method is to overcome these disadvantages and to enable the production of headers from a blank or tube of metal with a minimum amount of breakage and cracking, and with the thickness of the metal uniform throughout the header in its entirety. To this end the apparatus is generally in the form of a pair of die-holding members pivoted at one end and then moved gradually into engagement with the blank or tube having a mandrel therein. Pressure is therefore applied to one end of the blank or tube first and gradually, and then gradually and progressively to the remainder of the tube or blank until the end is reached. At the completion of the pressing movement of the die-holding members, the entire blank or tube will be engaged by the dies and the shaping operation completed. In addition to the side dies being constructed and arranged in this manner, the top die is similarly arranged and operated, that is, so that it has initial engagement with one portion of the tube or blank and progressive engagement with the remainder of the tube or blank, until the entire top surface thereof is engaged and pressed into its final formation.

Referring now to the drawings in which one embodiment of my apparatus is disclosed, the numeral 1 designates the base of the frame of the apparatus. This base forms a support for the various parts thereof. Centrally thereof is arranged and positioned an anvil or work-supporting member 2 which is of general T-shape, having the work-supporting head portion 3. The work supported on said head portion 3 is adapted to be operated upon by side dies and a top die. The side dies are designated generally by the reference character 4 having the forming part 5 and the base part 6, by means of which they are secured in a recess 7 in the holding and operating members 8. These holding and operating members 8 are of substantial and weighty construction, having the broad base portion 9 adapted to rest upon the base member 1 and to extend beneath the work-holding head 3 when in contact with the work and during the pressing operation. These two holding and operating members 8 for the side dies are pivoted to the rear end of the base 1 as at 10, being provided with the offset and reduced apertured bosses 11 and 12 for that purpose.

The top forming die is designated gen-

erally by the reference character 13 and is positioned and held in the top member 14, which extends toward the rear of the apparatus and is horizontally pivoted as at 15, being provided with the loop portion 16 to extend over and escape the pivot 10 and the apertured bosses 11 and 12.

In the apparatus shown, pressure is applied by means of manually-operated screw constructions. It is to be expressly understood that this showing is illustrative only and that pressure may be applied by hydraulic means, fluid pressure of various kinds or, in fact, any practical way. In order to permit the application of pressure by screws I provide yoke member 17 which has its free ends 18 attached at the sides of the base member 1 and has vertical side portions 19 and the horizontal top portion 20. A screw member 21 having the operating handle or wheel 22 is screw-threaded into each of the side members 19 of the yoke and has a rotatable engagement with the side die-holding and operating members, as at 23, whereby a rotation of the handle or wheel 22 results in movement of these members 8. A screw member 24 extends vertically in screw-threaded engagement with the top member 20 of the yoke and is provided with a handle or wheel 25, and has a rotatable engagement as at 26 (see Figure 7) with the top die-holding and operating member 14, so that when the handle or wheel 25 is rotated, the top die 13 will be moved.

Before proceeding to a description of the blank and the article made and the dies themselves, attention is particularly directed to the fact that the two side die-holding and operating members are pivoted at the rear of the apparatus, so that when pressure is applied to these members 8 by means of the screw members or equivalent means previously referred to, the side dies will be moved in gradually into engagement with the work, the first engagement taking place nearest the rear end of the machine, that is looking at Figure 3. Further application of pressure results in progressive engagement of the dies with the work, that is, progressive from the rear end toward the front end, and when the dies are forced into parallel relation with each other, which is their final position, the work, that is the blank or tube, will be engaged entirely along its length and, therefore, completely shaped by the side dies. It is also to be noted that the top die holding and operating member is pivoted at the rear and that the first engagement of the top die with the work will be at the rear and further application of pressure thereto will result in progressive application of die pressure to the work, that is the blank or tube, until the die is parallel to the base and the die-shaping operation complete with the top die in engagement with the work through-

out its entire extent. This results in the progressive application of shaping pressure to the work from the rear in toward the front end, so that the metal of the work will be subjected to gradually increasing pressure progressively from the rear in toward the front end, whereby it will give and be shaped without the abrupt changes due to the instantaneous application of pressure throughout its entire extent, as in the old apparatus and method.

One form of side die is shown in Figure 5 of the drawing and in that form the forming part is shaped so as to form a series of undulations in the side of the blank, these undulations being arranged at an angle or obliquely. The undulations on opposite sides of the completed header are arranged to complement each other so that the completed header is of substantially constant width throughout its entire length, being composed of alternate protuberances 27 and hollows or indentations 28 on one side which are located opposite the complementary hollows or indentations 29 and protuberances 30 on the other side of the header (see Figure 8). This construction is designed for use in an offset arrangement of boiler tubes, as is well understood.

One form of top die is formed as illustrated in Figure 6, as having a general wavy or undulatory shape, indicated at 31, that is looking at the sides, and having a serrated appearance formed by a plurality of inclines 32 leading to shoulders 33 formed by more abrupt inclines. These parts are offset as indicated in Figure 6 so as to correspond to the offset formation caused by the side dies, as above described. In other words, the top die provides a series of inclined surfaces or faces 32 terminated by rather abrupt shoulders 33, which are offset to correspond to the similar undulatory construction of the header as formed by the side dies.

In the forming operation, it is necessary to utilize a mandrel construction and this mandrel construction is illustrated in Figures 8, 9 and 10. It includes the bottom member 34 of sufficient length to fit entirely through the blank or tube and the top member 35 of the same length. The meeting edges of these two members 34 and 35 are on an angle so as to complement each other in having a wedgelike operation for insertion and removal. The top member 35 is formed with a plurality of comparatively gradual inclines or slopes 36 terminated by the abrupt inclines or shoulders 37 corresponding in shape to the top die with its inclines 32 and shoulders 33 and to the completed header, as shown in Figure 11. In order to provide mandrel means for the sides of the tube I utilize a divided member 38, the sides of which are formed in undulatory or wavy shape, as at 39, corresponding to

and complementary to the undulatory shape of the side dies. The two parts of this divided mandrel member 38 have beveled meeting edges 40 and reduced portions 41 fitting in and held in place by the main mandrel members 34 and 35, as clearly shown in Figure 10. This side mandrel construction is arranged so that a protuberance is formed in one side and directly opposite appears a hollow or indentation to correspond to the arrangement of the side die members previously described. It is therefore seen that this mandrel as a whole is of knockdown construction and readily placed in position and removed from the completed header. For removal it is only necessary to take out one of the members 34 and 35 and then the parts will drop so that the other members or parts of the mandrel can be readily removed. In view of the undulatory shape of the completed header and also the mandrel, the visible diameter of the opening or bore through the completed header is only a fraction of the actual cross-sectional diameter at any one place. The main parts of the mandrel 34 and 35 must be less in width than the visible width of the bore through the header, in order that they may be withdrawn. The undulatory side pieces of the mandrel 38, of course, when in position extend the full width of the bore of the completed header. However, they are much less in height than the height of the bore through the header because it is only necessary to resist pressure over a comparatively short distance. These side mandrel members, therefore, resist pressure sufficiently to enable the complete header to be shaped as a whole. Of course, making the side mandrel members thinner is an important factor in the removal of the mandrel as a whole. The character of blank used is not of material importance as long as it is hollow. Of course, the most usual form would be cylindrical or circular in cross-section, but this apparatus and method are readily applicable to other forms of blanks.

It is to be particularly noted that the arrangement of the die-holding members or arms, that is the pivotal construction of the same, is such as to cause the dies to initially engage the blank at one end and when these members are further actuated, the engagement will be progressive throughout the length of the blank to the other end, during which time the pressure upon the end first engaged will be increased and also the increased pressure will be applied progressively to the remainder of the blank. This is due to the scissors-like action or operation of the dies and die-holding members. When the shaping operation is complete, the dies for the sides of the header will be positioned in parallel relation and the top die will, in some cases at least, be in parallel relation

to the work support. Of course, if it is desired to form headers having inclined sides and top, or having these parts of other relative formations, this can be taken care of

5 by changing the dies and the position of the dies in the holding and actuating arms therefor.

Referring particularly to Figure 11 it is to be noted that the header itself in one

10 form has its top formed with a plurality of inclined faces or surfaces 42 terminated by more abruptly inclined shoulders 43 and that the sides of this header are undulated as indicated at 44 and 45, the undulations

15 being arranged to complement each other so that the header has the uniform internal diameter heretofore referred to. The inclined faces or surfaces 42 are slightly staggered or offset with relation to each other and are adapted to be bored as indicated at 46 to receive the boiler tubes, which will extend at an angle relative to the header.

Of course, it is obvious that other forms of headers may be made in which the faces

25 or seats for the boiler tubes will be straight or inclined differently and in which the side undulations may be straight or vertical with respect to the header as a whole, or inclined differently from those shown in the drawings. Furthermore, a header may be formed in which the top thereof is straight and flat and parallel with the bottom, in which event the side undulations are arranged vertically with respect to the header as a whole.

30 35 A very important advantage obtained by the use of the apparatus disclosed and in accordance with the method described is that the material of the blank is engaged slightly at the initial stage of the shaping opera-

40 tion, and as the pressure continues, the engagement of the dies with the blank will increase toward the other end and the part that the blank already engaged will be subjected to a greater shaping movement. Fur-

45 thermore, it is not until the shaping dies reach their ultimate or final position that the pressing or shaping operation is complete, and as the application of pressure begins at one end and this is initiated gradu-

50 ally toward the other end and the shaping movement of the blank begins at one end and is carried progressively and gradually to the other end, the metal of the blank will be able to accommodate itself to the shaping operation so as to avoid undue thinness and unevenness where the shaping pressure is the greatest.

55 It is to be noted that in Fig. 11 the upper inclined surfaces 42 of the completed header appear to be curved. This is an optical illusion due to the fact that the sides of the header are of curved wavy formation and these curved side lines, being concave and convex respectively, give this appear-

ance. The surfaces 42 are substantially straight.

What I claim is:—

1. The method of forming a boiler header including the operation of die-shaping a 70 stationary hollow blank with a mandrel therein by pressure of a plurality of dies applied progressively from one end of the blank to the other.

2. The method of forming a boiler header 75 including the operation of die-shaping a stationary hollow blank with a mandrel therein by pressure of a die on each side applied progressively from one end of the blank to the other.

3. The method of forming a boiler header including the operation of die-shaping a stationary hollow blank with a mandrel therein by pressure of a die on each side applied progressively from one end of the blank to 85 the other and of a top die applied progressively from one end of the blank to the other.

4. The method of forming a boiler header including the operation of die-shaping a 90 stationary hollow blank with a mandrel therein by pressure of a die on each side applied progressively from one end of the blank to the other, until the sides of the completely formed header are parallel. 95

5. The method of forming a boiler header including die-shaping a hollow blank with a mandrel therein by the scissors-like action of a pair of side dies engaging and pressing the sides of the blank progressively from 100 one end thereof to the other.

6. The method of forming a boiler header including die-shaping a hollow blank with a mandrel therein by the scissors-like action of a pair of side dies engaging and pressing the sides of the blank progressively from 105 one end thereof to the other, until the sides of the header are parallel to each other.

7. The method of forming a boiler header including die-shaping a hollow blank with 110 a mandrel therein by the scissors-like action of a pair of side dies engaging and pressing the sides of the blank progressively from one end thereof to the other, to form undulatory side faces arranged in stag- 115 gered relation to complement each other.

8. The method of forming a boiler header including die-shaping a hollow blank with a mandrel therein by the scissors-like action of a pair of side dies engaging and pressing the sides of the blank progressively from one end thereof to the other and the pressure of a top die applied progressively from 120 one end of the blank to the other.

9. An apparatus for forming boiler head- 125 ers, including a mandrel adapted to be inserted in a blank, a pair of holding and operating arms pivoted at one end, dies for shaping the sides of said blank provided in said arms, and means for actuating said 130.

arms and dies to engage and shape the sides of said blank progressively from one end to the other.

10. An apparatus for forming boiler head-
ers, including a mandrel adapted to be in-
serted in a blank, a pair of holding and oper-
ating arms pivoted at one end, dies for shap-
ing the sides of said blank provided in said
arms, and means for actuating said arms and
dies to engage and shape the sides of said
blank progressively from one end to the
other, the dies being parallel when the shap-
ing operation is completed so that the sides
of the blank are parallel when completed.

15 11. An apparatus for forming boiler headers, including a mandrel adapted to be inserted in a blank, a pair of holding and operating arms pivoted at one end, dies for shaping the sides of said blank provided in
20 said arms, and means for actuating said arms and dies to engage and shape the sides of said blank progressively from one end to the other, said dies having undulatory pressing faces arranged in staggered relation to complement each other in forming complementary undulatory side faces on said header.

12. An apparatus for forming boiler headers, including a mandrel adapted to be inserted in a blank, a pair of holding and operating arms pivoted at one end, dies for shaping the sides of said blank provided in said arms, means for actuating said arms and dies to engage and shape the sides of said blank progressively from one end to the other, and a top arm pivoted to the apparatus, a top die provided therein, and means for applying pressure to the top arm and die so as to engage the top portion of the blank progressively from one end to the other.

13. An apparatus for forming boiler headers, including a mandrel adapted to be inserted in a blank, a pair of holding and operating arms pivoted at one end, dies for shaping the sides of said blank provided in said arms, means for actuating said arms and dies to engage and shape the sides of said blank progressively from one end to the other, a top arm pivoted to the apparatus, a top die provided therein, and means for applying pressure to the top arm and die so as to engage the top portion of the blank progressively from one end to the other, the top die being parallel with the base of the apparatus when the shaping operation is completed so that the general plane of the top of the header is parallel with the general plane of the bottom of the header.

14. An apparatus for forming boiler headers, including a base, a work support on said base, a pair of side holding and operating arms pivoted to said base at one end, 65 dies for shaping the sides of a blank provid-

ed in said arms, a top arm pivoted near the same end of said apparatus, and a top die provided in said top arm, a mandrel adapted to be inserted in a blank held on the work support, and means for applying pressure to said side arms and said top arms so that the side dies and top dies engage the blank beginning at one end and pressure is applied progressively throughout the length of the blank to the other end.

15. An apparatus for forming boiler headers, including a base, a work support on said base, a pair of side holding and operating arms pivoted to said base at one end, dies for shaping the sides of a blank provided in said arms, a top arm pivoted near the same end of said apparatus, and a top die provided in said top arm, a mandrel adapted to be inserted in a blank held on the work support, and means for applying pressure to said side arms and said top arm so that the side dies and top die engage the blank beginning at one end and pressure is applied progressively throughout the length of the blank to the other end, said side dies being of undulatory conformation and staggered with reference to each other so that the completed header is formed with undulations on each side staggered with reference to the undulations on the other side. 80 85 90 95 99 995

16. In an apparatus for forming boiler headers, including a support for the work, a plurality of die holding and operating arms provided with dies, and means for forcing said arms and dies against the work, a mandrel adapted to be inserted within the work which is in the form of a hollow blank, said mandrel including a pair of longitudinally extending members and a pair of longitudinally and laterally extending members positioned and held therebetween, said laterally extending members having their outside edges formed with undulations, the undulations of one member being offset or staggered with reference to the undulations of the other member and corresponding to the shape of certain of the dies, said top longitudinal member of the mandrel being formed with a plurality of inclined surfaces terminated by shoulders formed by sharply inclined surfaces corresponding to the similar shape of the top die member.

17. The method of forming a boiler header including die-shaping a hollow blank by the scissors-like action of a pair of side dies, engaging and pressing the sides of the blank, the engagement and die-shaping beginning at one end of the blank and continuing progressively thereafter to the other end of the blank. 120 125

18. An apparatus for forming boiler headers, including a holding and operating arm pivoted at one end, a work support for supporting a blank, a die for shaping one face of the blank mounted in said arm, and means

- for actuating said arm and die to engage and shape the face of the blank beginning at one end and continuing progressively to the other.
5. 19. The method of forming a boiler header which includes applying pressure to the lateral and top sides of a stationary hollow blank progressively from one end of the blank to the other and forming diametrically opposed undulations in its sides and a plurality of inclined flat seats in its top side.
10. 20. The method of forming a boiler header which comprises subjecting a hollow blank while held on a mandrel in a stationary position to the die shaping action progressively from one end of the blank to the other.
15. 21. The method of forming a boiler header characterized by exerting pressure on a hollow blank progressively from one end of the blank to the other to bend the walls of the blank into a header of substantially rectangular cross section and provided in its lateral sides with diametrically opposed ridges and valleys and on its top side with a plurality of inclined flat seats, the pressure being exerted on substantially the whole length of the blank at the end of the operation.
20. 22. The method of forming a boiler header characterized by arranging a hollow blank over a mandrel having die portions, progressively bending portions in the lateral sides of the blank in engagement with said die portions from one end of the blank to the other so as to form diametrically opposed undulations.
25. 23. The method of forming a boiler header characterized by arranging a hollow blank over a mandrel and thereafter progressively bending portions in the lateral and top sides of the blank inwardly from one end of the blank to the other and forming its lateral sides with diametrically opposed undulations, and on its top side with flat seat faces disposed at an angle to the longitudinal axis of the blank.
30. 24. In an apparatus for forming boiler headers including a pair of holding and operating arms pivoted at one end, dies for shaping the sides of a blank held between said arms, means for actuating said arms and dies to engage and shape the sides of the blank progressively from one end to the other.
35. 25. An apparatus for forming boiler headers including a plurality of holding and operating arms pivoted at one end, dies provided in said arms for shaping the sides of a blank, means for actuating said arms and dies to engage and shape the sides of the blank progressively from one end to the other and a top arm pivoted to the apparatus, a top die provided therein and means for applying pressure to the top arm and die so as to engage the top portion of the blank progressively from one end to the other.
40. 26. An apparatus for forming boiler headers including a base, a work support on said base, a pair of holding and operating arms pivoted to said base at one end, dies provided in said arms for shaping the sides of a blank held on the work support and means for applying pressure to the arms which is transmitted to a blank from one end to the other to shape the blank into a header.
45. 27. An apparatus for forming boiler headers including a base, a work support on said base, a pair of holding and operating arms pivoted to the said arms for shaping the sides of a blank held on the work support, a top arm pivoted near the same end of said apparatus and provided with a top die, and means for applying pressure to said side arms and said top arm so that the side dies and top die engage the blank beginning at one end and pressure is applied progressively throughout the length of the blank to the other end.
50. 28. The method of forming a boiler header which comprises arranging a hollow blank over a mandrel having die portions, progressively bending portions in the lateral sides of the blank in engagement with the die portions from one end of the blank to the other so as to form diametrically opposed undulations in the lateral sides of the blank while applying pressure on the top side of the blank.
55. 29. The method of forming an article of the character described which comprises arranging a hollow blank over a mandrel and thereafter progressively bending portions in the lateral sides of the blank inwardly from one end of the blank to the other while applying pressure on the top and bottom sides of the blank so as to form a header of substantially rectangular shape in cross section and provided in its lateral sides with diametrically opposed undulations and on its top side with flat seat faces disposed at an angle to the longitudinal axis of the blank.
60. 30. The method of forming an article of the character described which comprises positioning a hollow blank on a mandrel having die portions, progressively bending portions in the lateral and top sides of the blank in engagement with said die portions from one end of the blank to the other so as to form diametrically opposed undulations in the lateral sides of the blank and flat seat faces on the top side of the blank.
65. In testimony that I claim the foregoing, I have hereunto set my hand this 6th day of February, 1928.
